UNITED STATES PATENT OFFICE

EDWARD E. BARTLETT, OF SAPULPA, OKLAHOMA, ASSIGNOR TO BARTLETT-COLLINS COMPANY, OF SAPULPA, OKLAHOMA, A CORPORATION OF OKLAHOMA

DESIGN FOR A TUMBLER OR SIMILAR ARTICLE

Application filed November 29, 1929. Serial No. 33,585. Term of patent 14 years.

To all whom it may concern:

Be it known that I, EDWARD E. BARTLETT, a citizen of the United States, residing at Sapulpa, in the county of Creek and State of Oklahoma, have invented a new, original, and ornamental Design for Tumbler or Similar Article, of which the following is a specification, reference being had to the accompanying drawing, forming a part thereof, in which the figure is a perspective view of a tumbler showing my new design.

The crescent-shaped decorations are formed on the inner surface of the tumbler.

I claim:

The ornamental design for a tumbler or similar article, as shown and described.

In witness whereof, I have hereunto set my hand.

EDWARD E. BARTLETT.
